UNITED STATES PATENT OFFICE.

WILLIAM LESCHMAN, OF CHICAGO, ILLINOIS, ASSIGNOR, BY MESNE ASSIGNMENTS, TO CHICAGO ELECTRIC MANUFACTURING COMPANY, OF CHICAGO, ILLINOIS, A CORPORATION OF ILLINOIS.

SPRING-RETRACTED ELECTRIC CIGAR LIGHTER.

Application filed December 6, 1923. Serial No. 678,895.

My invention relates to the general class of electrical appliances in which a current-consuming device has the current supplied to it through a flexible cord normally wound upon a spring-retracted reel. Generally speaking, it is the object of my invention to provide a simple, compact and effective appliance of this kind; and to provide a relatively inexpensive, easily installed and durable construction including simple and effective means for affording the needed circuit connections and for automatically interrupting the circuit when the current-consuming device has been retracted to a predetermined extent.

More particularly, my invention provides an appliance of this kind adapted to be supported by a dashboard or the like and so constructed as to have its major portions concealed behind such a dashboard; provides a cheaply manufactured and easily assembled spring-reel construction; provides means (desirably including a metal reel side) for carrying current to the current-consuming device when the latter is drawn out into position for use; and provides means actuated by the entry of a portion of the said device into a holder or socket for interrupting the circuit when this device is in its normally retracted and inoperative position. Still further and also more detailed objects will appear from the following specification and from the accompanying drawings, in which

Fig. 1 is a side elevation of an electric cigar lighter embodying my invention, showing the disposition of the same with respect to a portion of the dashboard of an automobile, this dashboard portion being indicated by dotted lines.

Fig. 2 is a front view of the same.

Fig. 3 is a plan view of the same appliance with the upper portion of the casing cut away and with the cigar lighter proper in its normal retracted position.

Fig. 4 is a plan view of the same appliance with the cigar lighter proper partly drawn out and with a portion of the top of the casing broken away to show how the circuit is then closed.

Fig. 5 is a fragmentary interior view of the side of the casing shown in Fig. 1, showing the switching member.

Fig. 6 is a section taken along the line 6—6 of Fig. 5. 55

Fig. 7 is a section taken along the line 7—7 of Fig. 5.

Fig. 8 is an enlarged vertical and transverse section taken through the axis of the reel, or along the line 8—8 of Fig. 3. 60

Fig. 9 is a similarly enlarged plan view of the reel, showing the same with the cord almost entirely unwound.

Fig. 10 is an end view of the reel, spring and spring anchoring cup, taken from the line 10—10 in Fig. 8 and with a portion of the anchoring cup for the inner end of the spring broken away to show the fastening of this end of the spring also.

Fig. 11 is a perspective view of the body 70 of the reel, showing the mounting of the metal ends on the wooden spool.

Fig. 12 is a perspective view of the wooden spool alone.

Fig. 13 is a perspective view of the anchoring cup to which the inner end of the 75 spring is secured.

Fig. 14 is a perspective view of the shaft before it is attached to the casing.

Fig. 15 is a fragmentary radial section 80 through the reel, showing a modified arrangement for preventing rotation of the cup which anchors the inner end of the spring.

Fig. 16 is a fragmentary view of my invention as embodied in a trouble lamp. 85

In its immediate commercial aspects, my invention is particularly suited for the construction of electric cigar lighters suitable for use upon automobiles. I am therefore 90 illustrating and describing it mainly in such an embodiment, although I do not wish to be limited to any particular application of the various novel features of the invention here presented.

In the drawings, Figs. 1 to 4 inclusive particularly show an embodiment in which the current-consuming device consists of a cigar lighter having a high resistance wire 1 mounted in the forwardly directed open 100 end of a casing 2, the terminals of this high resistance wire being connected respectively to the two strands or wires comprising a flexible cable 3. The mounting of the high resistance wire for this purpose, together 105 with the construction of the various parts

- of the cigar lighter form no part of my present invention, these being here shown to correspond to what is disclosed more fully in U. S. Patent #1,517,098, issued 5 November 25, 1924, to Edward S. Preston on an electric cigar lighter. The flexible cord 3 is normally wound upon a spring-retracted reel as hereafter more fully described, so as to draw the shank of the casing 2 into a tubular socket or holder member 4 to an extent which is limited by the engagement of a projecting bead 5 on the shank of the casing with the nut 6 which forms part of the means for clamping the entire 10 appliance to a dashboard 7. With this in mind, the appliance is provided with a hollow threaded shank 8 projecting forwardly from the front wall 9 of this casing, this shank being desirably integral with the socket 4 and hence secured jointly with the latter to the front wall 9 of the casing. This threaded shank extends through a suitable perforation in the dashboard 7 with the front wall 9 of the casing bearing 15 against the rear of the dashboard, and a nut 6 is threaded upon this shank so that the entire appliance can readily be clamped to the dashboard by merely tightening this nut from the front of the dashboard.
- 20 The casing of the appliance desirably has parallel side walls 10 and 11 each of which walls has one wire terminal supported by the same. Thus, the drawings show one circuit wire 12 as leading to a screw 13 mounted on one side of the casing while the end of the other circuit wire 14 is secured to the other side 11 of the casing by a binding screw 45 but insulated from this latter side.
- 25 One wall of the casing, shown in Fig. 6 as the wall 10, has a reel shaft rigidly secured to it and this shaft desirably has a base portion so formed as to cooperate with a suitable member for anchoring the inner end of a spiral spring 14 against rotation. For this purpose, I am showing the shaft 15 as having a square sectioned base 16 provided with a flattened extension 17. This extension 17 extends into a correspondingly shaped opening in the adjacent wall 10 and is staked 30 over against this wall at its outer end so as to anchor the shaft securely to the wall 10 after the manner shown in Fig. 8, thereby supporting the shaft from this one end and also preventing the shaft from rotating.
- 35 The cylindrical portion 15 of the shaft affords an axle for a wooden spool 18 which forms the hub of the reel and which has two metal end flanges fastened to it by screws, such as the screws 47 and 48. One of these flanges, namely the end flange 19 of Figs. 8, 9 and 11, is desirably flat and spaced from the wall 11 so as to permit the disposing of a movable switch portion between the said flange and wall. The other flange 20 desirably has its peripheral portion formed into

a cylinder 21 extending towards the wall 10 and normally bearing against the latter, while the flat flange 19 is kept at the desired spacing from the wall 11 by a smaller diameter extension 23 of the spool 18, which extension abuts against the wall 10 as shown in Fig. 8.

Operatively interposed between the stationary shaft and the reel is a spiral spring 14, which spring desirably has its outer end secured to the peripheral extension 21 on the flange 20. To secure the inner end of the spring against rotation, I desirably provide an anchoring cup having a base portion 25 provided with a square opening 48 which fits slidably over the square section casing 16 of the shaft. This cup has its lateral wall 26 of greater height than the width of the said flange extension 21, so as to serve for spacing the reel flange 20 and the said extension 23 freely from the wall 10. This cup wall 26 has a notch 27 formed into it from its free edge for receiving a portion of the shank of a button 28 which extends through a suitable perforation in the spiral spring 24 near the inner end of the latter. The peripheral portion 21 of the flange 20 also desirably has a corresponding notch 29 in the same for receiving a portion of the shank of a button 30 fastened to the spring 24 near the outer end of the latter.

The flexible cord 3 which normally is wound upon the reel as shown in Figs. 3 and 8 desirably has the inner end of both of its wires extending through a bore 30 (Fig. 9) into a recess 31 formed in the hub portion of the spool 18. One of these inner wire ends is desirably secured by a binding screw 32 to a lug 33 formed from the flange 20 and bent into the said recess 31, thereby connecting this wire to the metal of the reel and hence affording an electrical connection both through the flange extension 21 and through the shaft 15 to the wall 10 to which the circuit wire 12 is grounded. The other inner wire end desirably extends through a suitable perforation 50 (Fig. 11) in the flat flange 19 to the exterior of the latter and is secured to this flange by a screw 34 (shown in Fig. 9) so as to connect this wire to the flange 19 which is insulated from the other flange and from the casing by the wooden spool 18.

To make an interruptible circuit connection to this insulated flange 19, I provide a switching member electrically connected to the screw 45 and disposed for yieldingly engaging the said flange. For this purpose, I am here showing a resilient arm 35 mounted on but suitably insulated from the wall 11, this resilient arm 35 having a finger 36 which can be pressed against the flat metal flange 19 by the resiliency of the said arm. The arm 35 also carries a stud 37 insulated from the arm by an insulating bushing 38.

(as shown in Fig. 6) and normally extending through a bore 39 in the tubular socket 4 in which the shank 2 of the current-consuming appliance is normally socketed. 5 The arm 35 is so formed that its resiliency continuously tends to force the finger 36 into engagement with the flat metal flange 19 to which one wire of the flexible cord is connected and hence tends to make the electrical connection to the circuit wire 14 after the manner shown in Fig. 4. When doing this, the stud 37 projects for a considerable distance into the bore of the socket 4. However, when the current-consuming 15 device is retracted through the action of the spring, the shank 2 of the current-consuming device forces the stud 37 outwardly of the said socket or into the position shown in Fig. 3, thereby moving the contact finger 20 36 out of engagement with the flat reel flange 19 and hence interrupting the circuit. To facilitate this movement of the switching arm 35, I desirably slope the free end of the stud 37 after the manner shown in Fig. 6, 25 so that the rounded rear end of the shank 2 will exert a cam action on this stud. To insulate the switching arm from the casing wall 11 to which it is fastened, I desirably interpose an insulating plate 40 between it 30 and the wall 11 and also provide a companion insulating plate 41 bearing against the outer face of the wall 11. Then I secure the said parts to each other by rivets 42 and 43 after the manner shown in Fig. 7 35 and thread one of these rivets so as to receive the wire-screw 45, the rivets being kept out of engagement with the wall 11 by their extending through perforations of a considerably larger diameter than the shanks 40 of the rivets.

With the parts thus constructed, it will be evident from the drawings that they permit a speedy assembling of the various parts and that the number of fastening elements required is quite small. The reel portion can be assembled before the insertion in the casing after the manner shown in Figs. 9 and 11, and the shaft 15 can be riveted to the wall 10 of the casing, which wall desirably is formed integral with the front wall 9. Then the two ends of the spring can be interlocked respectively with the reel flange rim 21 and with the anchoring cup 25 as shown in Fig. 10, after which the reel 50 with the spring and the said anchoring cup connected to it are slid into position over the shaft from the free end of the latter, or from the right in Fig. 8. The reel is then turned until the spring has been suitably wound or tightened, after which the flexible cord is drawn through the socket 4 and through the perforation 30 in the hub of the reel and has the ends of its two wires secured respectively to the lug 33 on the flange 20 55 and to the flat flange 19. Then the wall 11

with the switching member (which switching member includes the arm 35) already secured to the same as shown in Fig. 5 and with the peripheral wall portion 46 also fastened to it is slipped into position and fastened to the other casing portion by screws 44, thereby permanently closing the casing to retain the reel in its operative position and to prevent tampering with the mechanism. 70

However, while I have heretofore described my invention in an embodiment including various highly desirable features of construction, I do not wish to be limited to the details of construction and arrangement thus disclosed, since these might obviously be varied in many ways without departing either from the spirit of my invention or from the appended claims. Thus, Fig. 15 shows another form of anchoring cup designed for use with a shaft which has no square sectioned portion, namely one having a lug which enters a corresponding perforation in the adjacent wall of the casing so as to prevent the cup from rotating about the shaft. 75

Neither do I wish to be limited to the use of my spring reel construction and of my automatic switching arrangement with an electric cigar lighter as the current consuming device, since other devices might readily be substituted for this portion of the appliance. For example, Fig. 16 shows my appliance as employed in connection with a flash lamp or so-called trouble lamp. 80

I claim as my invention:—

1. The combination with a current-consuming device and a pair of flexible conductors leading thereto, of a stationary tubular member in which a portion of the said device is normally socketed, a reel for the conductors, the reel having a metal side portion forming a terminal for one of the conductors, spring means for rotating the reel to wind the conductors thereon and to retract the said portion of the device into the said shell, the current-consuming device having a portion thereof engaging a rigid part of the said tubular member to limit the retraction of the said device, a stationary wire terminal, and a resilient switching member controlling the circuit through the conductors, the switching member having a contract portion forced into engagement with the said reel side portion by the resiliency of the switching member when the said device is drawn out of the said tubular member, the switching member also having an actuating portion extending laterally into the said tubular member and so disposed as to have its said contact portion moved out of contact with the said reel side when the current-consuming device is retracted into the said tubular member. 110

2. An electric appliance as per claim 1, in 115

which the tubular member has a lateral perforation and in which the actuating portion of the switching member extends through the perforation into the tubular member and is yieldingly pressed laterally inwardly of the tubular member by the resiliency of the switching member.

3. An electric appliance as per claim 1, in which the tubular member has a lateral perforation and in which the actuating portion of the switching member extends through the perforation into the tubular member and is yieldingly pressed laterally inwardly of the tubular member by the resiliency of the switching member, the said actuating portion having an inclined face engaged by the current-consuming device with a cam action when the latter is drawn into the said shell.

4. The combination with a portable current-consuming device, of a holder normally socketing the same, a pair of flexible conductors leading to the device, a spring-retracted rotatable reel upon which the conductors are normally wound, means for continuously connecting one side of an electric circuit to one terminal of the device, a contact element carried by the reel and connected to the other terminal of the device, and a resilient switching member connected to the other side of the circuit, the switching member having a portion disposed for

engaging the contact element and another portion urged by its resiliency transversely into the holder and disposed for being moved by engagement with the device when the latter is being socketed so as to open the circuit.

5. A combined holder and retractor for a portable current-consuming device having a shank at its rear end and for a pair of flexible conductors leading to the device; the said holder and retractor comprising a stationary support, a holder member mounted on the support and having a tubular portion slidably entered by the said shank and provided with a lateral aperture, a reel including a hub rotatably mounted on the support and a metal reel side, spring means for rotating the reel to wind the conductors thereon, a contact member yieldingly engaging the metal reel side, and means including an element extending through the said aperture into the path of the entering shank of the device and adapted to be moved laterally out of the holder by engagement with the said shank during the socketing of the latter in the holder so as to move the contact member out of engagement with the metal reel side.

Signed at Chicago, Illinois, November 30th, 1923.

WILLIAM LESCHMAN.
